UNITED STATES PATENT OFFICE.

JOSEPH STRAND, OF LOS ANGELES, CALIFORNIA, ASSIGNOR TO KLINCH LATH CORPORATION, OF LOS ANGELES, CALIFORNIA, A CORPORATION OF CALIFORNIA.

DOUBLE-WALL WALL-BOARD CONSTRUCTION AND SPACING MEMBER THEREFOR.

Application filed December 21, 1925. Serial No. 76,662.

My invention relates to wall constructions using the well known wall or plaster board. In the usual form of wall construction using wall board, the wall board sheets are nailed 5 to the opposite sides of timber studs of the wall construction, whereafter a coating of plaster is applied to the exterior sides of the wall board sheets, thus finishing the wall. Wall board partitions may be made very 10 cheaply, without the use of studs, by employing vertical wall board retaining members extended from the floor to the ceiling, engaging side edges of the wall board sheets and holding them in place. Both sides of 15 the wall board sheets are given a coating of plaster, thus forming a complete partition.

Partitions of this character are quite often used in place of wall constructions because of the factor of economy, although 20 they are not by far as satisfactory. Partitions are not entirely satisfactory because they are not wholly stable or sound-proof and do not have heat insulation characteristics to speak of. A large item of expense 25 in wall constructions is the cost of installation of the timber studs.

It is an object of my invention to provide a wall construction, using wall board, which does not require timber studs as a component. 30

It is another object of this invention to provide a novel form of spacing and bracing member for use in timberless wall constructions for the purpose of properly spacing 35 the opposing sheets of wall board and for bracing and rigidifying the wall construction.

Other objects and advantages will be made evident hereinafter.

40 Referring to the drawing in which I illustrate a preferred form of my invention,

Fig. 1 is a perspective view showing a spacing member which performs an important function in the wall construction of my 45 invention.

Fig. 2 is a horizontal sectioned view of a wall construction embodying the features of my invention.

Fig. 3 is a fragmentary view taken as indicated by the arrow 3 of Fig. 2.

Fig. 4 is a fragmentary section taken on the line 4-4 of Fig. 3.

Referring particularly to Fig. 2, the wall construction of my invention consists of a 55 primary wall 11 and a secondary wall 12.

The walls 11 and 12 are formed from sheets of wall members 14 which are in this case sheets of wall board. Extending vertically between the vertical edges of the sheets of wall board 14 are vertical retaining members 15. These retaining members 15 may be of any satisfactory construction, the ones shown consisting of a web 16 which rests between the vertical faces of adjacent sheets of wall board and flanges 17 which extend 60 from opposite edges of the web 16 in opposite directions and in positions to contact faces of the sheets of wall board 14. The vertical wall board retaining members 15 are substantially reverse Z-shape as shown in 70 Fig. 2. Secured to the web 16 of the retaining members 15 are ears or tongues 19 which may be bent into the position shown in the drawing to cooperate with an opposite flange 17 for holding the wall board in place. 75 These vertically extending wall board retaining members ordinarily extend from the floor to the ceiling and retain the sheets of wall board 14 in a common vertical plane. In the past the wall board retainers 15 were 80 used only in single wall construction or partitions.

The primary and secondary walls 11 and 12 are held in proper parallel spaced relationship and are braced by spacing members 85 22. Referring to Fig. 1, each of the spacing members 22 consists of a U-shaped member having a web or back 23 from the opposite edges of which legs 24 extend in planes at right angles to the web 23 and parallel to each other. Near each end of each of the spacing members 22 is a retaining channel 26 and extending outward from the bottoms of these channels at each side therefrom are wings 27. These wings 27 extend outward 90 from the web 23 and are in the same plane as the web 23. The retaining members 22 may be very cheaply produced from rectangular sheets of metal such as indicated by dotted lines 29 of Fig. 1 which may be stamped to the shape shown in full lines in Fig. 1. 100

These spacing members 22 are placed so that the horizontal edges of the sheets of wall board rest in the channels 26. As 105 shown clearly in Fig. 4 the retaining members 22 are placed so that corresponding horizontal edges of opposing sheets of wall board rest in channels 26 of the same spacing member 22. The edge faces of the wall 110

boards rest against the portions of the web 23 which form the bottoms of the channels 26 and against the faces of the wings 27 which extend in the same plane as the engaged faces of the webs 23. In practice the spacing members 22 are placed on the upper and lower horizontal edges of the opposing sheets of wall board 14 in staggered relationship as shown clearly in Fig.

10 3. Therefore, the web portions 23 of the staggered spacing members 22 rest in the same plane and therefore only a minimum gap is left between the adjacent horizontal faces of the sheets of wall board.

15 The channels 26 are of the same width as the thickness of a wall board or may be slightly narrower so that the legs 24 may firmly grip the horizontal edges of the wall board. These members 22 not only retain 20 the upper and lower horizontal edges of the sheet of wall board in proper spaced relationship, but tie the primary and secondary walls 11 and 12 together which makes them quite rigid. The wings 27 provide a large 25 engagement face and contact with the horizontal edge faces of the sheets of wall board and thus prevent any twisting whatsoever of the spacing members 22.

A coating of plaster 32 is then applied to 30 the exterior of each of the faces of the primary and secondary walls 11 and 12. In Fig. 2 only the secondary wall 12 is shown plastered. As shown in Fig. 4 the ends of 35 the spacing members 22 extend from the exterior faces of the primary and secondary walls 11 and 12 and thus provide a tying means for the plaster which assists in securing the plaster to the exterior faces and prevents creeping.

40 From the foregoing description it is evident that my invention eliminates the use of timber studs in double wall constructions, and makes it possible to provide a wall construction of this character much cheaper 45 than has ever been produced. In place of the timber studs and the nailing of the sheets of wall board to the studs I employ the vertically extending wall board retaining members 15 and the spacing members 22 which 50 are quite economical as compared with the timber studs and the nailing of the sheets of wall board in place.

I claim as my invention:

55 1. In a wall construction, the combination of: a primary wall composed of sheets of wall members; a secondary wall composed of sheets of wall members, said secondary wall being spaced directly adjacent to said primary wall and substantially parallel thereto; primary retaining members extending vertically between the vertical edges of the sheets of wall members of said primary wall, engaging and retaining them in a common vertical plane; secondary retaining members extending vertically between the vertical edges of the sheets of wall members of said

tical edges of the sheets of wall members of said secondary wall, engaging and retaining them in a common vertical plane; and spacing members connected to said primary and secondary walls at points where the horizontal edges of the wall members of the respective walls meet.

2. In a wall construction, the combination of: a primary wall composed of sheets of wall members; a secondary wall composed of sheets of wall members, said secondary wall being spaced directly adjacent to said primary wall and substantially parallel thereto; primary retaining members extending vertically between the vertical edges of the sheets of wall members of said primary wall, engaging and retaining them in a common vertical plane; secondary retaining members extending vertically between the vertical edges of the sheets of wall members of said secondary wall, engaging and retaining them in a common vertical plane; and spacing members having channels formed therein for receiving horizontal edges of the opposing sheets of wall members of said primary and secondary walls for spacing and bracing said walls.

3. In a wall construction, the combination of: a primary wall composed of sheets of wall members; a secondary wall composed of sheets of wall members, said secondary wall being spaced directly adjacent to said primary wall and substantially parallel thereto; primary retaining members extending vertically between the vertical edges of the sheets of wall members of said primary wall, engaging and retaining them in a common vertical plane; secondary retaining members extending vertically between the vertical edges of the sheets of wall members of said secondary wall, engaging and retaining them in a common vertical plane; members for spacing and bracing the opposing sheets of wall members of said primary and secondary walls, each of said members having spaced channels adapted to receive corresponding edges of opposing sheets of wall members; and wings extending outward from the channels of said members, said wings extending in planes parallel to the horizontal edges of said sheets of wall members and in contact therewith.

4. In a wall construction, the combination of: a primary wall composed of sheets of wall members; a secondary wall composed of sheets of wall members, said secondary wall being spaced directly adjacent to said primary wall and substantially parallel thereto; primary retaining members extending vertically between the vertical edges of the sheets of wall members of said primary wall, engaging and retaining them in a common vertical plane; secondary retaining members extending vertically between the vertical edges of the sheets of wall members of said secondary wall, engaging and retaining them in a common vertical plane; and spacing members connected to said primary and secondary walls at points where the horizontal edges of the wall members of the respective walls meet.

secondary wall, engaging and retaining them in a common vertical plane; **U**-shaped members for spacing and bracing the opposing sheets of wall members of said primary and 5 secondary walls, each of said **U**-shaped members having spaced channels adapted to receive corresponding edges of opposing sheets of wall members; and wings extending outward from the channels of said **U**-shaped 10 members, said wings extending in planes parallel to the horizontal edges of said sheets of wall members and in contact therewith.

5. A combination as specified in claim 4 in which said wings consist of portions of said 15 **U**-shaped members extended outward in order to provide said channels.

6. A spacing member for double wall board construction, said member comprising: an elongated **U**-shaped body providing a base 20 wall and opposite parallel side walls, said side walls being slotted near their opposite ends to provide parallel transverse channels each adapted to receive a wall

board; and side wings in the plane of said base wall and extending in opposite directions transversely and in alignment with the respective channels, the side walls between said channels serving as means for maintaining said wall boards in relative spaced relationship, and the side wall portions beyond 25 said channels serving as means for retaining said wall boards against relative separation. 30

7. A spacing member for double wall board construction, said member comprising: an elongated **U**-shaped body providing a base 35 wall and opposite side walls, said side walls being transversely slotted at relatively spaced intervals to provide parallel channels, and said base wall being extended in opposite transverse directions adjacent each channel to provide side wings. 40

In testimony whereof, I have hereunto set my hand at Los Angeles, California, this 15th day of December, 1925.

JOSEPH STRAND.
